UNITED STATES PATENT OFFICE

GRENVILLE E. JONES, OF ST. LOUIS, MISSOURI, ASSIGNOR TO GENERAL STEEL CASTINGS CORPORATION, OF GRANITE CITY, ILLINOIS, A CORPORATION OF DELAWARE

LOCOMOTIVE-TENDER STRUCTURE

Application filed October 24, 1929. Serial No. 402,101.

My invention relates to railway rolling stock and consists in a novel locomotive tender construction and more particularly in a tender underframe adapted to form all, or 5 a substantial part, of the bottom of the tender tank and adapted to mount stoker mechanism.

One of the objects of my invention is to provide an underframe, having the characteristics referred to, which is as wide as the 10 tank structure and is provided with sills at its sides located high enough above the rail to permit access under the side sills and adjacent bottom portion of the underframe and over the truck wheel pieces below the under- 15 frame.

Another object of my invention is to provide a bolster and center sill construction for such an underframe which will form water compartments.

20 Another object of my invention is to construct an underframe having side sills and adjacent structure as described and will also have an intermediate structure adapted to mount stoker mechanism at a lower level than 25 the top of the side sills.

Another object of my invention is to provide for manual access through an underframe forming a water compartment whereby 30 operators can get at stoker mechanism from beneath the underframe.

These and other detailed objects of my invention are attained by the structure illustrated in the accompanying drawings in which—

35 Figure 1 is a top view of a locomotive tender underframe, an intermediate part of the same being broken away to facilitate the illustration.

Figure 2 is a longitudinal vertical section 40 taken approximately on the center line of the underframe.

Figures 3 and 5 are end views of the right hand and left end of the underframe as shown in Figures 1 and 2.

45 Figures 4, 6, 7, 8, 9 and 10 are vertical transverse sections taken on the corresponding section lines of Figure 1.

The underframe preferably comprises a one-piece casting, although it may be made 50 of two or more units riveted to each other or

welded together in order to form an integral structure and it is within the scope of my invention that the forward part of the underframe, or even the stoker mechanism receiving portion of the underframe, be made as a 55 single unit, irrespective of the rest of the underframe.

The main members of the underframe are the side sills 1, the end sills 2, bolsters 3, the box-shaped center sill 4 and intermediate 60 sills 5. These sills are connected by a substantially continuous lower web member 6 which also forms the bottom of the center sill and the bolsters.

Horizontal flanges 7, 8, 9, 10 and 11 form 65 suitable reinforcement for the upper portion of the tender frame and some of these flanges, such as best shown in Figures 1, 4 and 7, extend across the bolster and center sill and connect the upper portions of the right hand 70 bolster and center sill and adjacent intermediate sill 5 and form the bottom of a compartment 12 adapted to receive stoker mechanism which I have indicated generally at S. In order to provide for the location of the 75 stoker mechanism on the tender in alignment with or at the same height as the stoker mechanism on the engine, the portions of these flanges which form the bottom of the stoker compartment are depressed below the level of 80 the top of the bolster and center sill and side sill top flanges in order to accommodate the stoker mechanism at a lower level than would be possible if the top face of the underframe was in the same plane from side sill to side 85 sill and from end to end. A portion of the bottom of the stoker compartment is provided with a pad 13 on which a wear plate 14 is mounted to provide a track for the stoker mechanism S and this plate may be 90 renewed, when desired.

The tender side sheets are riveted or welded to the side sills as shown in Figure 7 and together with the sills form side girders for carrying the loads at the side of the tank; 95 and as a result of this construction the depth and weight of the side sills are much less than would be necessary for an open type tender frame for a tank having the same capacity. Other advantages of the shallow 100

side sills for my underframe structure are that the bottom of each side sill is a substantial distance above the level of the bottom of the center sill and above the truck frame or wheel piece T, the top of side sills are the same height or level as the highest portions of the center sills and bolsters, and web 6 extends inwardly of the underframe from the bottom of side sill 1 for a substantial distance to provide access to the truck parts by means of the space between the web and truck frame wheel piece. Within the truck side frame, member 6 extends downwardly and inwardly to the bottom of the center sill. This arrangement of web, sills and bolsters provides a construction that is much simpler than one where the top of sills and bolsters would be lowered to the level of the bottom of the stoker compartment, as the web 6 which extends inwardly from the bottom of the side sills would have to be made with large recesses on the underside to provide for access between the same and the truck side frame.

The stoker recess is wider at the front end than at the inner end as shown at 31, so as to accommodate the drive shaft 32 when the stoker apparatus swings laterally relative to the underframe while the locomotive is on a curve.

The side of the stoker compartment is formed, in part, by the offset 15 in flange 10 and, in part, by a suitable plate 16 mounted on the flange 10 by welding direct or by means of a connecting angle 17 which may be riveted or welded to the plate and flange. The top of the stoker compartment and bottom and side of coal compartment is formed by a horizontal plate 18 which extends laterally and upwardly (not shown) to the tank side plate 19 riveted or welded, or otherwise secured, to the side sill 1.

All of the space below top plate 18, and to the outside of upright plate 16, forms a water compartment extending along the side of the stoker compartment and this water compartment is extended downwardly and inwardly through the underframe throughout the length of the bolster and throughout the length of the center sill. At the bolster, the lower web 6 of the underframe is provided with pads 20 for mounting suitable side bearings. At the sides of the bolster, the lower web 6 may incline more directly from the side sill to the center sill as best shown in Figure 8. This construction provides for the drainage of the water in the tank to the center of the underframe whereby substantially all of the water may be drawn off, if necessary.

It is desirable to get at the stoker mechanism without draining the water from the tank and without necessarily removing all of the coal from the fuel compartment and I provide such accessibility by forming suitable openings 21 and 22 by means of upright webs 23 and 24 extending transversely between

the center sill and the adjacent intermediate sill 5. These openings also permit the passage of dirt from the bottom of the stoker compartment through the underframe.

In order to facilitate the molding of a cast tender frame, such as I illustrate, I provide the various webs with suitable openings 28 and, after the casting is completed, core sand may be removed through these openings and the openings thereafter closed by means of plates 29 preferably welded over the same.

Additional features of the preferred structure are the integral step 25 and integral safety chain lug 26 and suitable members 27 forming a draft pocket. At 30, I illustrate a center plate structure which is adapted to facilitate lubrication of the truck and body center plate elements but this lubrication features does not form any part of my present invention.

The details of my invention may be modified without departing from the spirit thereof and I contemplate the exclusive use of such variations in the construction as come within the scope of my claims.

I claim:

1. A tender underframe having a depression in the top thereof adapted to accommodate a stoker apparatus.
2. In a tender underframe, an end sill, said end sill being depressed at its central portion so as to accommodate a stoker apparatus.
3. In a tender underframe, a bolster, said bolster being depressed at its central portion so as to accommodate a stoker apparatus.
4. In a tender underframe, a bolster, an end sill, said bolster and end sill being depressed at their central portions so as to accommodate a stoker apparatus.
5. In a tender underframe, a longitudinal center sill, a portion of the top of said sill being depressed so as to accommodate a stoker apparatus above the same.
6. In a tender underframe, a bolster, an end sill, a center sill, said bolster and end sill being depressed at their central portions and said center sill being offset downwardly at its front end, said offset portion extending between said end sill and bolster and rearward of said bolster, said depressed portions and offset adapted to accommodate a stoker apparatus.
7. In a tender underframe, side sills, structure intermediate said sills, a portion of said structure being offset downwardly below the level of the top of said sills so as to accommodate a stoker apparatus.
8. In a tender underframe, a center sill, a side sill, and a horizontally disposed top member connecting said sills, a portion of said center sill and member being depressed below the remainder thereof and below said side sill to accommodate a stoker mechanism.
9. In a tender underframe, a center sill including a lower horizontal web, said center

sill forming a water compartment, a portion of said sill being of reduced height and a horizontal top web over said portion forming a stoker compartment bottom wall below 5 the level of the top of said sill beyond the end of the stoker compartment.

10. A tender underframe comprising side sills, a center sill, a bottom web, and top flanges, all forming a liquid reservoir, there 10 being a depression in the upper portion of said underframe for mounting stoker mechanism.

11. In a tender underframe forming the bottom of the tender tank and adapted to 15 contain liquid, longitudinal members, a bolster, there being a depression in said members extending from the front end of the underframe to a point at the rear of said bolster, said depression being arranged to 20 accommodate a stoker apparatus.

12. In a tender underframe forming at 25 least a portion of the bottom of the tender tank and adapted to contain liquids, a box shaped center sill extending rearwardly from the front end of the underframe, the top of 30 said sill being offset downwardly for a portion of its length at its front end so as to accommodate a stoker apparatus, said sill being adapted to contain liquids substantially 20 throughout its length.

13. In a tender underframe, forming at 35 least a portion of the bottom of the tender tank and adapted to contain liquids, a box shaped center sill extending rearwardly from the front end of the underframe, the top of 40 said sill being offset downwardly for a portion of its length at its front end, a box shaped bolster spaced from the front end of said casting, and having a depressed upper face intermediate its ends, said sill and said bolster being adapted to contain water and said offset and depressed portions being adapted to accommodate a stoker apparatus.

14. In a tender underframe including 45 members provided with a longitudinally extending recess adapted to accommodate a stoker apparatus, and renewable wear plates on said members adapted to support said stoker apparatus.

50 15. In a tender underframe, a web forming the bottom and at least a part of the side wall of a stoker compartment, and other members spaced from said web and forming therewith a water reservoir in said underframe at the side of and above the level of 55 the bottom of said compartment.

16. In a tender underframe, sills and webs forming a water compartment, and upright elements between said sills and webs forming 60 a passageway from the lower portion of the underframe to the upper portion thereof to provide manual access to mechanism mounted on the upper portion of said underframe.

65 17. In combination, a locomotive tender underframe forming at least a portion of the

bottom of the tender tank and adapted to contain liquids, tank sheets secured to said underframe and extending upwardly therefrom and forming a compartment for a stoker apparatus, a box shaped center sill 70 forming part of said underframe and located intermediate said sheets and forming one of the liquid compartments of said tank, and an opening in said underframe casting between said sill and one of said sheets and providing access to said stoker compartment. 75

18. In a tender underframe extending substantially throughout the width of a tender tank, a side sill, a deeper center sill, and a web extending inwardly from said side sill 80 horizontally to a point inside of the wheel gauge and then downwardly to the bottom of said center sill.

19. In a tender underframe extending from side to side of the tender tank, side sills, 85 and a box shaped bolster between said sills, said bolster forming a water receiving compartment from end to end.

20. In a tender underframe, a center sill including upper and lower horizontal webs, 90 said center sill forming a liquid compartment, a portion of the top web of said sill forming a stoker compartment bottom wall.

21. In a tender underframe, members provided with a longitudinally extending recess 95 adapted to accommodate a stoker apparatus and a renewable wear plate located in said recess and adapted to support said stoker apparatus.

22. In a locomotive tender, an underframe 100 forming at least a portion of the bottom of the tender tank and adapted to contain liquids, tank sheets secured to said underframe and extending upwardly therefrom and forming a compartment for a stoker apparatus, a box shaped center sill forming part of said underframe and located intermediate said sheets and forming one of the liquid compartments of said tank. 105

23. In a tender, an underframe, an end sill, side sills, structure intermediate said side sills, a portion of said structure being offset downwardly below the level of the top of said sills so as to accommodate a stoker apparatus, said offset portion extending longitudinally inwardly from said end sill and having a greater width at the end sill portion than at its inner end. 110

24. In a locomotive tender, an underframe 115 having sill members and webs forming a liquid compartment, plates mounted on top of said underframe comprising a housing for stoker mechanism, said plates forming a closed wall between said compartment and said mechanism, and upright elements between said members and webs forming substantially vertical openings through said underframe to provide manual access to said mechanism, at least a portion of said under- 120 125 130

frame below said mechanism being adapted to contain liquid.

25. In a tender underframe adapted to contain liquid, a center sill, a bottom web plate, means provided on the top of said underframe to support a stoker housing, there being a vertical opening at the side of said sill through said underframe leading into said housing for access to the stoker mechanism.

26. In a tender underframe forming at least a portion of the bottom of the tender tank and adapted to contain liquid, a portion of the top of said underframe having a horizontal web forming the bottom wall of a stoker compartment, there being openings formed in said web for manufacturing purposes, and means for closing said openings, so as to adapt said underframe portion below said web to contain liquid.

27. In a locomotive tender, an underframe forming at least a portion of the bottom of the tender tank and adapted to contain liquid, and including a box shaped center sill, a box shaped bolster, a portion of the top wall of said center sill and said bolster forming a bottom wall of a stoker compartment, an opening in said center sill and said bolster for manufacturing purposes, and means for closing said opening so as to adapt the portion of said center sill and bolster below stoker compartment to contain liquid.

28. In a tender underframe, a bolster, an end sill, a center sill, said bolster and end sill being depressed at their central portions and said center sill being offset downwardly at its front end, said offset portion extending between said end sill and bolster and rearward of said bolster, said depressed portions and offset adapted to accommodate a stoker apparatus, all of said parts being integral with each other.

In testimony whereof I hereunto affix my signature this 21st day of October, 1929.

45 GRENVILLE E. JONES.
